UNITED STATES PATENT OFFICE.

THOMAS P. BOLGER, OF GLOUCESTER, MASSACHUSETTS.

ASH-SIFTER.

949,615.

Specification of Letters Patent. Patented Feb. 15, 1910.

Application filed February 8, 1908. Serial No. 414,945.

To all whom it may concern:

Be it known that I, THOMAS P. BOLGER, a citizen of the United States, residing at Gloucester, in the county of Essex and State 5 of Massachusetts, have invented a new and useful Improvement in Ash-Sifters, of which the following is a specification.

This invention relates to an ash sifter, and the object of the invention is a device of 10 this kind having a rotary sifter open at each end and inclosed in a casing, one end of said casing being closed by a gravity-drop door which is automatically opened by pressure 15 of coal against it, thereby making the sifter as dust tight as a device of this kind can be made and at the same time leave a conveniently arranged discharge opening discharging into a common coal scuttle.

The invention consists of the novel features of construction hereinafter described, 20 pointed out in the claim and shown in the accompanying drawings in which—

Figure 1 is a side elevation of my device, parts of a coal scuttle and ash receiver being 25 broken away. Fig. 2 is a longitudinal vertical section through the device as shown in Fig. 1. Fig. 3 is a plan view of the device mounted in position as shown in Fig. 1. Fig. 4 is a section on the line 4—4 of Fig. 2. 30 Fig. 5 is a sectional view on the line 5—5 of Fig. 2 looking toward the discharge end of the device.

In these drawings 1 represents a suitable casing which is provided with a flanged 35 cylindrical base 2 adapted to fit over a barrel or metal ash can 3. At one end of the casing 1 it is carried upwardly forming a hopper 4 provided with a hinged top 5. A flanged sliding cover 6 closes the top of the 40 body portion of the casing 1 and is held in place by a turn button 7 carried by an end 8. Extending longitudinally entirely through the casing 1 is a rotatable shaft 9 provided at the hopper end of the casing with a handle 10. At the opposite end of the casing, 45 which end extends beyond the circular base 2, is provided a downwardly opening discharge outlet 11, the bottom of the casing adjacent said discharge outlet being downwardly inclined as shown at 12. Hinged 50 within the casing is a gravity-drop door 13 the lower free edge of which rests upon the

inclined portion 12 of the casing bottom and said door is vertically slotted as shown at 14 to permit passage of the shaft 9 and also 55 to allow for the swinging movement of said door.

Within the hopper 4 is arranged a fixed screen 15, said screen having a downwardly inclined bottom spaced from an inclined 60 bottom portion 1^a which bottom portion is directly below the hopper 4. The inner end portion of the screen 15 is semi-cylindrical and is carried by a fixed metal ring 16.

The shaft 9 is provided with arms 17 arranged in sets and one set of arms carries a collar 18 arranged concentrically with respect to the ring 16 and turning loosely upon the ring. The other set of arms 17 are arranged adjacent the gravity-drop door 13 70 and support a collar 19 and upon the collars 18 and 19 is arranged a rotatable screen 20 the rear end of said screen being of smaller diameter than the front end.

A hook 21 is carried by the end 8 upon 75 which may be hung the bail of a coal scuttle or other receptacle.

The operation of the device is as follows:—The ashes to be sifted are poured into the hopper 4 and the top 5 closes. The 80 handle 10 is then turned and the screen 20 turns with the shaft 9. The fine ashes which fall through the fixed screen 15 upon the inclined bottom 1^a will slide at once into the barrel or can 3. The remainder of the coal 85 and ashes will slide into the rotating screen 20 and the ashes will be sifted therein from the coal and will fall through into the ash receiver and the coal will be carried on to the end of the screen 20 and will fall upon 90 the inclined bottom portion 12. The weight of these coals will open the door 13 and permit them to fall through the outlet 11 into the scuttle 22, the door again closing by gravity when the weight against it is removed. Should strings, rags or other articles be in the coal and ashes and interfere with the sifting operation, the top 6 can be slid off and the interfering articles may be removed. The screen 20 can be readily 100 lifted out for cleaning should it become clogged up, by drawing out the shaft 9, which will slide through its bearings.

Having thus fully described my invention,

what I claim as new and desire to secure by Letters Patent, is:—

5 An ash sifter comprising a casing having a hopper at one end and a discharge opening at the other, a fixed screen in alinement with the hopper, a ring carried by the inner end of the fixed screen, a rotatable shaft extending longitudinally through the cas-

ing and through said ring, arms carried by the shaft, collars carried by said arms, one 10 of said collars turning loosely upon the ring and a screen carried by said collars.

THOMAS P. BOLGER.
